J. CRNOEV

NECKTIE HOLDER

1,445,611

Filed June 17, 1922

UNITED STATES PATENT OFFICE.

JAN CRNOEV, OF ST. LOUIS, MISSOURI.

NECKTIE HOLDER.

Application filed June 17, 1922. Serial No. 569,115.

To all whom it may concern:

Be it known that I, JAN CRNOEV, a citizen of Serbia, residing at Saint Louis, Missouri, have invented a certain new and useful Improvement in Necktie Holders, of which the following is a full, clear, and exact description, such as will enable others skilled in the art to which it appertains to make and use the same, reference being had to the accompanying drawings, forming part of this application.

My invention relates to devices of the type shown in my prior Patent No. 1,400,663, issued December 20, 1921, and consists in improvements on this patented holder, which simplify the construction and facilitate the positioning of a necktie in relation to the collar.

Other objects of my invention are to enable the user of my device to eliminate re-tying and consequent wrinkling of a necktie whenever it is desired to make a change, or the alternative of duplicating the complete holder device. This object is obtained by making the holder in two parts, the tie holding part of which may be duplicated.

In the accompanying drawings which illustrate a preferred construction of my invention, and several modifications thereof,—

Figure 1 is a front elevation of my improved holder showing it applied to a collar and having a necktie knotted thereon.

Figure 2 is a side elevation of the same.

Figure 3 illustrates a modification of the collar button engaging portion of my device.

Figure 4 shows a different type of necktie carrying elements.

Figure 5 is a side elevation of another form of holder mounting member.

Figure 6 is a vertical section through another modified form of holder mounting member.

In the preferred construction illustrated in Figures 1 and 2, the collar button is formed in two parts, one part comprising the shank 1, head 2, base 3, and the other part comprising a male snap element 4. The base 3 is provided with an opening extending transversely of the shank and slidable in this opening is an element 5, the upper part of which is bent downwardly at 6 to engage the upper edge of the collar and then bent upwardly as at 7 to support a

link 8 on the lower end of which is pivotally mounted one arm 9 of a V-shaped member of flexible material. The other arm 10 extends upwardly.

A Y-shaped member of flat material has its arms 11 shaped to extend into the folds of the collar and its leg 12 extending downwardly in the plane normally occupied by a necktie and preferably folded so as to surround the upwardly extending arm 10 of the V-shaped member carried by link 8. It will be understood that the necktie can be knotted upon the Y-shaped member independently of the assembly of the latter with the other portions of the holder, and, if desired, a number of Y-shaped members may be provided for the permanent knotting of a like number of ties, that is, each tie will have its individual Y-member which may be slipped on and off of the arm 10.

Element 5 is slidable in the collar button to provide for adjustment to accommodate different heights of collar and the Y-member is slidable upon arm 10 to similarly provide for adjustment of the necktie relatively to the collar button in order that the necktie knot may be neatly seated in the collar folds. While the frictional contact between arm 10 and leg 12 may be sufficient to retain the latter when desired, I may insure the positioning of the parts by providing leg 12 with a projection 13 adapted to enter any one of a series of perforations 14 in arm 10.

In the use of my device, it will be found most comfortable to place the clasp member 4 on the inside of the inner neck band A of the shirt, placing the button base 3 on the outside of the inner shirt band, thus clasping the inner band between parts 3 and 4. The outer shirt band and the collar bands may then be slipped over the shank of the collar button in the usual manner.

In the construction illustrated in Figure 3, the hook-like member of the preferred form is omitted and link 15 corresponding to link 8 of Figures 1 and 2 is pivoted on a female clasp member 16 which is adapted to clasp on the head 17 of a rigid collar button possessing the fixed shank 18 and base 19. In this form, the friction between the curved spring link arm 20 of the V-shaped member and the leg of the Y-member is presumably sufficient to retain the latter in any adjusted position.

The form illustrated in Figure 4 dis-

closes a Y-member in which the arms 22 and 23 are complemented by arms 24 and 25, arms 23 and 25 being pivotally assembled at 26 and arms 24 and 22 being provided with mutual engaging elements 27 and 28. At the convergence of arms 24 and 25, a single spring element 29 is slidably mounted and is frictionally engaged by the sides of the slot through which it passes. The upper end of element 29 is provided with an opening 30 which adapts it to engage the hook of the vertical member carried by the collar button.

In Figure 6 I illustrate a collar button 31 and a hooked vertical member 32 in which the collar button is in one piece and is not detachable from the hooked member. In this form the upper part of the hook member will go next to the wearer's neck, although slightly spaced therefrom by the base of the button. Mounted upon the head 33 of the collar button are pointed hooks 34 adapted to engage the inner face of the outer fold of a soft collar to hold the front of the latter together.

In Figure 5 a further modification of my invention is disclosed, the collar button and hooked member being here united in a single vertical element 35, the lower end of which is bent outwardly and terminates in a head 36 large enough to prevent unwanted retraction of the head through the button holes of a collar and shirt band. Collar holding hooks 37 are formed from a spring wire device and are slidably mounted upon element 35. On this device which is flat I mount a collar holding device comprising two hook portions 37 united by a spring section 38 which provides sufficient flexibility between the hook portion to enable them to be moved from the full line position to that shown in dotted line which permits them to be slipped off and on member 35. These parts are formed from a single length of spring wire. A link 39 limits the outward movement of the hooks which the tension spring 38 tends to give them.

In all of the different forms of my device, the adjustable and interchangeable features referred to in the beginning of the specification are retained and the manufacturing simplified by the utilization of flat material instead of the wire construction shown in my prior patent. I contemplate such additional modifications of my invention as fall within the scope of the spirit thereof as expressed in the appended claims.

I claim as my invention:

1. A necktie holder comprising a collar button supported hook, an element pivotally suspended therefrom, and a necktie carrying member carried by said element.

2. An adjustable necktie holder comprising an element adapted to be secured to a collar button, suspension means depending therefrom, and a necktie carrying member adjustably mounted on said means.

3. An adjustable necktie holder comprising an element adapted to be secured to a collar button, suspension means depending therefrom, and a necktie carrying member slidably mounted on said means, and frictional elements on said means and member for yieldingly retaining said member in desired position.

4. A necktie holder comprising a collar button, an opening therein extending transversely of the button shank, a member slideable through said opening, a link pivoted to the upper end of said member, a flexible element mounted on said member, and a necktie carrier adjustably secured to said element.

5. In a necktie holder, means attachable to a collar button and provided with a downwardly and outwardly projecting portion, and a Y-shaped necktie carrying member, the ends of which are adapted to extend into the folds of a collar and the leg of which is adjustably mounted on the projecting portion of said means and about which a necktie knot may be formed.

6. In a necktie holder, means attachable to a collar button and provided with a vertical portion of flat material, a Y-shaped necktie carrying member, the arms of which are adapted to extend into the folds of a collar and the leg of which is doubled transversely to surround downwardly projecting portion, and cooperating projections and depressions on said leg and portion to hold said parts in desired predetermined relation.

7. In a necktie holder, a collar button, a member slideable up and down in said button and bent at its upper end to engage the upper edge of a collar and present an upwardly facing hook beyond the collar, a link suspended from said hook, a V-shaped member pivoted by one arm to the lower end of said link, and a necktie carrying element slidably mounted on the other arm of said V-shaped member.

In testimony whereof I hereunto affix my signature this 9th day of June, 1922.

JAN CRNOEV.
